UNITED STATES PATENT OFFICE.

JULIUS SPIEGEL, OF BERLIN, GERMANY, ASSIGNOR TO GENERAL ELECTRIC COMPANY,
A CORPORATION OF NEW YORK.

WATER-JACKET FOR INTERNAL-COMBUSTION ENGINES.

1,112,337.

Specification of Letters Patent. Patented Sept. 29, 1914.

Application filed May 31, 1911. Serial No. 630,360.

To all whom it may concern:

Be it known that I, JULIUS SPIEGEL, a subject of the King of Great Britain, residing at Berlin, Germany, have invented certain new and useful Improvements in Water-Jackets for Internal-Combustion Engines, of which the following is a specification.

The invention relates to water jackets for cooling the cylinders of internal combustion engines and more particularly to jackets for the cylinder heads and the adjacent ends of the cylinders.

The object of the invention is the provision of an improved jacket structure which is efficient, simple, inexpensive, and which permits the cylinder heads to be readily removed for inspection of the interior of the cylinder and related parts.

In the accompanying drawing, Figure 1 is a section of the end of an engine cylinder; and Fig. 2 is a partial side view of an engine.

The cylinder 3 is provided with a jacket 4 and with passages 5 and 6 through which 25 the charge is admitted to the cylinder and the exhaust passes out from the cylinder. In the engine chosen for the purpose of illustrating the invention, the flow between these 30 passages and the cylinder is controlled by a tubular valve 7 which slides in the bore of the cylinder between the wall of the bore and the piston, said valve being actuated by any suitable mechanism. The outer end of the cylinder is closed by a head 8 which projects into the cylinder and carries packing 35 rings 9 for the valve 7. The head is provided with a centrally arranged hollow member 10, the inner end of whose wall merges with the inner end of the wall of the 40 head and whose outer end projects outwardly beyond the flange on the head. A spark plug or other igniting device can be mounted in the portion 11 of this member if desired, free access to the outer end of the 45 member being afforded so that connections can be made to said device. A cover 12 having flanges 13 that fit against the end of the cylinder outside of the flange on the cylinder head or heads has also an opening 50 or openings 14 into which the outer end or

ends of the members 10 are fitted. The contour of the outer edge of the cover conforms to the general outline of the cylinder or group of cylinders of the engine, as shown in Fig. 2. The cover is held in place by the 55 nut or nuts 15.

The construction described provides an annular cooling-water space 16 in the cylinder head between its inner and outer walls which is in communication with the space 60 inclosed between the cover 12 and the end or ends of the cylinders. These spaces can be connected to the cooling water circulating system of the engine in any suitable manner. When access to the interior of the 65 cylinder is desired for inspection, etc., the nut or nuts 15 are unscrewed and the cover 12 taken off, thus giving free access to the cylinder head or heads and to the interior 70 of the cylinder or cylinders when the heads are removed.

The invention is not limited in its application to the particular type of engine shown in the drawing, nor to an engine having any particular number of cylinders.

What I claim as new and desire to secure by Letters Patent of the United States, is,—

1. In combination, a cylinder, a head that closes the end of the cylinder, said head having a centrally arranged hollow member with a cooling-water space between it and the outer wall of the head, a cover for the head that fits against the end of the cylinder and incloses a cooling-water space between 80 it and the end of the cylinder that is in communication with the first mentioned space, said member having a cylindrical portion projecting outwardly through the cover, and a nut on said portion that holds the cover 85 in place.

2. In combination, a cylinder, a head that closes the end of the cylinder and has a hollow cylindrical portion that projects into the bore of the cylinder, a tubular valve 95 mounted in the bore of the cylinder between said portion and the wall of the bore, a centrally arranged hollow member within the head whose wall merges with the wall of said portion adjacent the inner end thereof, 100

a cover for the head that fits against the end of the cylinder and incloses a cooling-water space between it and the end of the cylinder that is in communication with the space between the inner and outer walls of the head, said hollow member having a cylindrical portion that projects outwardly through the cover, and a nut in threaded

engagement with said cylindrical portion that secures the cover in place.

In witness whereof, I have hereunto set my hand this 6 day of May, 1911.

JULIUS SPIEGEL.
